UNITED STATES PATENT OFFICE.

JAMES M. CRANZ, OF BUFFALO, NEW YORK.

DESIGN FOR A TIRE TREAD.

Application filed December 28, 1922. Serial No. 4,739. Term of patent 7 years.

To all whom it may concern:

Be it known that I, JAMES M. CRANZ, a citizen of the United States, residing at Buffalo, in the county of Erie and State of New York, have invented a new, original, and ornamental Design for Tire Tread, of which the following is a specification, reference being had to the accompanying drawing, forming a part thereof.

In the accompanying drawing showing my new design:

Fig. 1 is a face view of a tire tread embodying my new design.

Fig. 2 is a cross section of the tread portion of the tire on line 2—2, Fig. 1.

I claim:

The ornamental design for a tire tread, as shown.

JAMES M. CRANZ.
